DESIGN FOR A GAME BOARD OR SIMILAR ARTICLE

Joseph T. Cukor, Tuckahoe, N. Y.

Application May 15, 1936, Serial No. 62,653

Term of patent 14 years

To all whom it may concern:

Be it known that I, Joseph T. Cukor, a citizen of the United States and a resident of Tuckahoe, in the county of Westchester and State of New York, have invented a new, original, and ornamental Design for a Game Board or Similar Article, of which the following is a specification, reference being had to the accompanying drawing, forming part thereof.

The figure is a plan view of a game board showing my new design, the game board being of no appreciable thickness and the game features being substantially flush with the surface of the board.

I claim:

The ornamental design for a game board or similar article substantially as shown and described.

JOSEPH T. CUKOR.
